UNITED STATES PATENT OFFICE.

NATHAN KRAMER AND BENJAMIN KRAMER, OF TRENTON, NEW JERSEY, ASSIGNEES
TO TRENTON AUTO RADIATOR WORKS, OF TRENTON, NEW JERSEY, A FIRM.

AUTOMOBILE RADIATOR.

Application filed June 28, 1918. Serial No. 242,460.

To all whom it may concern:

Be it known that we, NATHAN KRAMER and BENJAMIN KRAMER, citizens of the United States, residing at Trenton, in the 5 county of Mercer and State of New Jersey, have invented certain new and useful Improvements in Automobile Radiators, of which the following is a specification, reference being had therein to the accompanying drawing.

This invention relates to certain new and useful improvements in automobile radiators and more particularly to a construction of core therefor, the object being to provide 15 a core having vertically disposed zigzag water passages and horizontally disposed rectangular air passages in order to produce a radiator which is exceedingly simple and cheap in construction and one which has a 20 high cooling efficiency.

Another object of our invention is to provide a core which is formed of strips of brass plaited to form rectangular air passages and indented to form substantially V-shaped depressions so that when arranged 25 in staggered relation with the duplicate strip thus formed vertically disposed water passages will be provided.

Another object of our invention is to provide 30 a fin formed of a straight strip of metal which forms a fourth side to the rectangular air passages, said strip being independent of the water passages in order to enable the same to be formed of a cheaper material.

Other and further objects and advantages 35 of the invention will be hereinafter set forth and the novel features thereof defined by the appended claims.

40 In the drawings,

Figure 1 is an elevation of a portion of a radiator constructed in accordance with our invention;

Figure 2 is a vertical section showing the 45 vertically disposed zigzag water passages and horizontally disposed rectangular air passages;

Figure 3 is a section taken on line 3—3 of Fig. 2; and

50 Figure 4 is a perspective view of a portion

of a core of a radiator constructed in accordance with our invention.

Figure 5 is a vertical section through a slightly modified form of radiator.

Figure 6 is a section taken on line 6—6 55 of Fig. 5; and

Figure 7 is a detail view showing the manner of positioning the ribs on the fin strips.

Like numerals of reference refer to like parts in the several figures of the drawing. 60

In carrying out our invention we employ upper and lower water chambers 1 and 2 between which is arranged a core having vertically disposed zigzag water passages 65 communicating with the water chambers 1 and 2 and horizontally disposed rectangular air passages extending from the front to the rear of the radiator in order to expose the side walls of the water passages to the air passing through said air passages. 70

In forming the vertically disposed water passages I employ two strips of brass or analogous material, two and one-half to five inches wide and of any length desired according to the size of the radiator to be 75 constructed. Each strip is plaited to form outwardly projecting plaits 3 forming three sides of an oblong. The face of each strip is indented to provide a depression 4 which terminates short of the edges of the strips as 80 clearly shown in perspective view in Fig. 4 in order to provide a strip having a series of depressions in one face thereof and a series of laterally extending ribs upon the opposite face. The strips thus formed are then 85 placed face to face in stepped relation to provide a zigzag water passage 5 adapted to extend from the upward water chamber to the lower chamber as clearly shown in Fig. 2. 90

These strips are preferably secured together by solder or any other suitable means and arranged against the edges of the plaits 3 is a plate 6 of substantially the same size as the strip previously described, said strip 95 being formed of any suitable material as this strip forms a fin to complete the oblong air passage 7 and is not exposed to the cooling medium employed in the radiator so that it can be formed of cheaper material. 100

In constructing a complete radiator we have shown one manner of assembling these strips in which the upper and lower water chambers are connected together by plates 8 which in this instance performs the function 5 of the fins 6 and by arranging a pair of strips in stepped relation with the faces in contact with one another a zigzag water passage is produced separated by horizontally disposed oblong air passages so as to 10 allow the side walls of the water passages formed by the depressions to be exposed to the air currents passing through said air passages.

15 The straight marginal edges of the strips of brass are arranged in contact as shown in Fig. 4 and by this construction a radiator core is provided which can be manufactured very cheaply as it is only necessary to have 20 one set of dies to form a strip into the desired shape as by arranging the strips thus formed with their faces in contact with one another and in stepped relation vertically disposed zigzag water passages are formed 25 and in conjunction with the fin in the form of a flat plate or strip of material oblong air passages are provided for allowing a free circulation of air to pass the walls of the water chamber.

30 In Fig. 5 I have shown the several elements arranged in respect to each other so that the plaits 3' and depressions 4', instead of being arranged in stepped relation with one another, are arranged in the same horizontal plane whereby substantially vertical 35 water passages are formed having constricted portions. By arranging the strips in this manner a different design is obtained and a construction is provided which has a 40 high cooling efficiency.

In order to provide means for supporting the plaits of the strips, I provide a fin strip 6' having at each edge upon opposite faces, a projection 6² which is formed by punching 45 the metal outwardly from opposite sides whereby a concaved depression is formed on one face of the strip and a convexed boss upon the opposite face. When the strips with the depressions and plaits are arranged 50 as shown in Figs. 5, 6 and 7, the plaits will rest on the bosses, as clearly shown, and by constructing the fin strips in this manner, the cells of the radiator can be properly positioned so as to produce water passages having 55 constricted portions and horizontally disposed air passages.

From the foregoing description it will be seen that we have provided an automobile radiator with a core formed of duplicate 60 strips arranged face to face in order to provide vertically disposed zigzag water passages in order to retard the flow of water in its circulation through the radiator so as to obtain a high cooling efficiency.

65 It will also be seen that by the plaiting of

these strips three sides of an oblong are formed which is completed by a fin in the form of a flat strip or plate so as to provide substantially oblong horizontally disposed air passages.

We claim:

1. An automobile radiator having a core provided with vertically disposed zigzag water passages and horizontally disposed air passages, the vertically disposed water 75 passages being formed of duplicating strips arranged in stepped relation with one another having contacting faces, each strip having a series of laterally extending plaits upon one face, and a series of depressions 80 upon the opposite face in different horizontal planes, and flat fins arranged to engage the ends of the plaits to form substantially oblong air passages.

2. An automobile radiator having a core 85 provided with vertically disposed zigzag water passages and horizontally disposed substantially rectangular air passages, the water passages being formed of duplicate strips having contacting faces, the contacting faces of said strips being provided with recesses substantially V-shaped in cross section, said strips being arranged in stepped relation with one another, the outer faces 90 of said strips having laterally extending plaits between the enlargements formed by said recesses forming opposite sides of an oblong and flat fin arranged to engage the edges of said plaits forming the third side 95 of said oblong.

3. A radiator having a core formed of plaited strips to produce laterally extending horizontally disposed plaits, said strips having recesses between the ribs, in the opposite faces of said strip from the ribs two 100 of said strips being arranged in contact in stepped relation to produce a zigzag vertically disposed water passage, and flat fins arranged against the edges of said plaits forming horizontally disposed substantially 105 rectangular air passages.

4. An automobile radiator having a core 110 formed of duplicate plaited strips provided with recesses in the opposing faces thereof, said strips having contacting faces and arranged in stepped relation with one another to produce a vertically disposed water passage, the plaits of said strip extending from the opposite face of the strip containing the recesses and flat strips arranged against the 115 edges of the plaits forming horizontally disposed substantially rectangular air passages.

5. An automobile radiator composed of an upper and lower water chamber having a core arranged between said chambers provided with vertically disposed zigzag water 120 passages communicating with said water chambers, and horizontally disposed oblong air passages extending from the front to the rear of said radiator, said core being formed 125

- of duplicate plaited strips and fins, said strips having recesses formed in the opposing faces thereof, the faces of each pair of said strips being arranged in contact with 5 one another and in stepped relation, the faces and recesses being arranged in different horizontal planes and upon opposite sides of said strip, said fins being arranged to engage the edges of the plaits.
- 10 6. An automobile radiator having a core provided with vertically disposed water passages formed of duplicate strips arranged in stepped relation with their faces in contact with one another, said strips being provided with horizontally disposed plaits upon one face and recesses in the opposite face, said recesses forming a portion 15 of the wall of the vertically disposed water passage said plaits forming opposite sides 20 of the walls of each air passage, the plaits and recesses being arranged in different horizontal planes the fins being arranged against the edges of the plaits to form the third side of each horizontally disposed air 25 passage.
7. An automobile radiator having a core formed of duplicate plaited strips provided with recesses in the faces thereof, each pair of strips having contacting faces to produce 30 a vertically disposed water passage, the recesses and plaits of said strips being ar-
- ranged upon opposite sides of said strip and in different horizontal planes, and flat strips arranged against the edges of the plaits forming horizontally disposed air passages. 35
8. An automobile radiator having a coil provided with vertically disposed zig-zag water passages and horizontally disposed substantially rectangular air passages, the vertically disposed water passages being 40 formed of duplicate strips arranged in stepped relation with one another and having connecting marginal portions secured together, each strip having a series of laterally extending plaits upon one face extending the full width of the strip and a series of embosses in different horizontal planes terminating short of the edges of the strip and forming upon the opposite face of the strip a series of depressions and flat 45 fins arranged to engage the ends of the plaits to form substantially rectangular air 50 passages.
- In testimony whereof we hereunto affix our signatures in the presence of two witnesses. 55
